(57) **CLAIM**

The ornamental design for a tool for cutting an optical fiber, as shown and described.

DESCRIPTION

FIG. 1 is a perspective view of a tool for cutting optical fiber, showing my new design;

FIG. 2 is a left side elevation view thereof;

FIG. 3 is a top plan view thereof;

FIG. 4 is a bottom plan view thereof; and,

FIG. 5 is an enlarged front end elevation view thereof.

1 Claim, 5 Drawing Sheets

FIG. 1

FIG. 2

FIG. 3

FIG. 4

FIG. 5
